IMPROVEMENT IN TRAVELLING BAGS.

E. A. G. ROULSTONE, OF ROXBURY, MASSACHUSETTS.

Letters Patent No. 60,255, dated December 4, 1866.

SPECIFICATION.

TO ALL WHOM IT MAY CONCERN:

Be it known that I, E. A. G. ROULSTONE, of Roxbury, in the county of Norfolk, and State of Massachusetts, have invented certain new and useful Improvements in Travelling Bags; and I do hereby declare that the following, taken in connection with the drawings which accompany and form part of this specification, is a description of my invention sufficient to enable those skilled in the art to practise it.

In the manufacture of travelling bags or portmanteaus, a great demand exists for an article that can be furnished at a very cheap price. Now, in the ordinary methods of construction so much nice work and manipulation is involved in forming and connecting the parts, that with the ordinary prices for good workmanship the bags cannot be made at such cost as will enable them to be sold excepting at seemingly very high prices. To reduce this cost of construction, and at the same time to form a bag of neat appearance, and in which all the connections are as strong and durable as is the material of the body of the bag, is the object of my invention.

In the production of these articles cheaply, the principal cost is in the construction of the metal frames which form the closing-jaws, and in the method of connecting these frames to the bag leather or body, and my invention has particular reference to this matter, and also to the locking mechanism which connects the frame to the formation of the body itself, and to the construction of the ears or bearing pieces fastened to the frame, and supporting the hinge-rod upon which the two parts of the bag open and shut.

The drawing represents at A a cross-section of a bag embodying my improvements; B is a view of the inner side of the frame, where the lock is applied to the same, showing the arrangement of the bolt; C is a perspective of one corner of the body of the bag; D an inside view of one corner of the frame; E a sectional view of one of the bearings of the hinge-rod; F G H are detail views of modifications of the frame construction.

For more readily understanding the construction, I have represented the bag as divested from a lining, or rather as formed without a lining, the common application of which is only changed so far as may be obviously necessary by the peculiarities of my formation.

a a denote the two parts of the bag body; *c d* the frames to which the same are applied, these frames being hung upon a wire hinge-rod, *e*, in the usual manner; this rod extending out from the frame and being supported at each end in a bearing piece *f*, as seen at E. In the usual manner of applying this rod to the bearings, the rod extends entirely through the same, and has its ends upset or rivetted over, to keep the rod in place. This construction is imperfect, however, in that these ends, extended through the bearings, form sharp points, against which surfaces catch, and are by wear and abrasion constantly becoming loose, and work out from the bearings. To remedy this difficulty, I form a screw-thread on each end of the rod, as seen at E, and form in the bearing a counter screw-thread, but do not extend this latter thread through the bearing. Now, by screwing the bearing upon the end of the rod, it will be obvious that when the bearing is fastened to the frame by the rivet *g* the rod is not only secured from displacement, but that there are no projecting points extending from the same. Each frame piece, *c d*, is made up of an inner plate *h*, and an outer one *i*, each bent longitudinally to the form of the top and ends of the bag. The inner piece *h* has a flange or lip, *k*, turned in from it, this lip being flat, as seen at A F G, or in the form of a bead, as seen at H. The opposite edge of the lip is turned partially round, as seen at *l*, and the adjacent edge of the plate or piece *i* has a counter turn, as seen at *m*. Between the adjacent surfaces of the plates *h i* the edge of the leather or bag body is inserted, a fold or turn made at the edge of the leather being enclosed in the groove made by the two bent edges of the pieces *h i*, as seen at A. Now, after forming the body *a*, its edges are simply placed between the plates, (with the turned edge in the groove formed by both,) and the two plates and body are then secured together by a row of rivets *n*, this arrangement enabling me to place the leather in position without drawing the edge through a groove made up of one piece, and without any stitching, while the bent edges of the plate at the same time give strength and stiffness to the frame. The specific construction shown at A may be varied somewhat, as seen at F G H, but in each there is this peculiarity of construction, that the connection of the leather to the frame is protected by a lip or bead turned from one or both plates, and not turned wholly around the edge, but only partially around or relatively to the same.

In applying the lock to the frame, I extend the bolt *x* through a slot *p* in the frame, as seen at B, the bolt working to and fro in (not to and from) this slot, by which means all strain upon the frames, when locked together, to force them apart, is received against the frame, and makes it impossible, or almost impossible, to force or break the lock.

To form each corner of the frame piece *i*, (and whether this piece constitutes an inner or outer or sole frame piece,) I cut the plate, and reinforce the joint as follows: I first bend the plate to form the flange or lip *k*, when the piece is straight, and then at the point where the corner is to be formed I cut out a piece of such form as to make a mitre butt joint *q*, when the piece is bent longitudinally to the required right-angular shape. Previously or subsequently to these bending and cutting operations I cut two slits *r* through the plate at the transverse angle, and so as to extend on each side of the mitre joint, as seen in the drawing, *D*. Then having cut a flat piece of metal to extend under and both sides of this joint, as seen at *s*, I turn up from the same a lip *t*, which I bend to fit the inner bent surface of the corner plate; and extend this lip through the slit *r*, so as to lay against the inner surface of the corner plate, while the part covering the joint is applied to the opposite surface of the flange, and is riveted to the flange, as seen at *D*, thus forming a stay, and protecting and strengthening the corner.

In all bags of this nature heretofore made the body *a* is made up of several pieces of leather, or (other material used for its construction,) involving a multiplicity of seams. To reduce the number of these I cut the material to such form that both parts, *a a*, are made from one piece, portions being cut out where the corners are to be formed, the sides left by such cut being brought together and joined by stitches, as seen at *C*, and the central part being drawn around the hinge wire, and stitched over the top of the same, as seen at *A*.

I claim the combination and arrangement of the inner and outer plates *h i*, making up one-half of the frame, when so constructed and applied to the body *a*, inserted between them, that from one or both of them a lip is turned down, which shall protect or cover the edge of the body, without either lip passing around or enclosing the edge, the plates and body being secured together substantially as shown and described.

I also claim the corner stay piece, when constructed and applied substantially as described.

Also the construction of the bearings *f*, with a screw-thread extending only partly through the bearing, so as to secure and protect the hinge-rod, substantially as described.

Also so applying the lock to the frame that its bolt works in a slot in the frame, substantially as shown and described.

Also in a bag, made up of two parts *a a*, applied to frame *c d*, forming the bag body from one piece, substantially as set forth.

E. A. G. ROULSTONE.
